UNITED STATES PATENT OFFICE.

DAVID ROBINSON, OF CLEVELAND, OHIO, ASSIGNOR TO NATIONAL MALLEABLE AND STEEL CASTINGS COMPANY, OF CLEVELAND, OHIO, A CORPORATION OF OHIO.

CAR COUPLING.

Application filed December 20, 1924. Serial No. 757,225.

My invention relates to car couplings, and particularly to couplings used for mine cars. Nearly all mine cars are equipped at the present time with link and pin couplings and, as it is the practice not to turn the cars end for end, the coupling heads are so arranged that the coupling on one end of each car carries a link and the other coupling does not, so that the coupling with the link is always opposed by a coupling without a link. As such couplings are non-automatic, it is necessary to raise the coupling pin by hand, and sometimes to guide the link into the pocket, and then drop the pin. This, obviously, is a dangerous proceeding and occasions frequent injury to the car operators.

The present invention obviates these objections by providing for automatic coupling and for manual uncoupling which may be effected through an ordinary uncoupling rod connection. My invention also comprises the various features which I shall hereinafter describe and claim.

Fig. 1 is a section showing a pair of couplings embodying my invention with the parts in locked position; Fig. 2 is a section of the operating coupler head similar to Fig. 1, but with the parts in uncoupled position, the entering link being just about to strike the trigger which supports the coupling pin in uncoupled position; Fig. 3 is a plan of the link head, partly in section; Fig. 4 is an elevation thereof; Fig. 5 is a plan of the link; and Fig. 6 is a plan, partly in section, of the operating head.

Referring to the drawings, A indicates the link coupler-head, and B the operating coupler-head. The link head A has a pocket 2, in which a link 3 is permanently and pivotally mounted on the vertically disposed pivot pin 4. The link 3 has apertures 3^a for the pin 4, and 3^b for the pin 14, and is able to swing laterally about the pin 4 through an arc of approximately 180°, since the mouth 5 of the pocket extends not only across the front of the head A but also a distance along each side thereof, so as to permit the link 3 to be swung substantially at right angles to the line of draft to prevent it from projecting out of the link head when run onto a mine elevator, as otherwise the overall length of the car might be too great for the elevator. The link 3 can also tip up and down within the limits provided by the

diverging top and bottom walls 6 and 7 of the pocket 2, which permit a substantial degree of vertical angling of the link 3 to take care of track conditions or variations in the heights of the couplings.

The rear surface 8 of the link is preferably arc-shaped, and is engaged by the correspondingly shaped forward face 9 of the spring plunger 10, which is mounted in the throat 11 of the link head A. The plunger 10 is always kept in contact with the rear face 8 of the link 3 and so holds the link 3 in a horizontal position ready for coupling, and tends to return it to such position when coupled after vertical angling.

The operating head B is of the same general shape as the head A. It has a pocket 12, a locking pin 14, and a mouth 15 for the pocket, which, however, does not extend into the side walls of the head. It has also diverging top and bottom walls 16 and 17 which permit the same degree of vertical angling as do the corresponding walls in the head A.

The locking or coupling pin 14 is loosely mounted in the guides 18 in the top and bottom walls of the pocket 12, and is pivotally connected to trigger mechanism 19 by a pin 14^a. The trigger 19 preferably has a pair of laterally extending trunnions 20 intermediate its ends which seat in longitudinal slots or grooves 21 in an upward extension 22 of the head. The grooves 21 have an intermediate hump 23 and terminate at their forward ends in the recesses 24. At the forward end of the trigger 19, and preferably forward of its pivotal connection with the pin 14, is a clevis 25 or other means for the attachment of the uncoupling mechanism by which the trigger 19 and pin 14 may be lifted.

To uncouple, the trigger 19 and pin 14 are raised by the clevis 25 until the bottom of the pin 14 has cleared the aperture 3^b in the link 3, as is shown in dotted lines in Fig. 1. Meanwhile, as the trigger is lifted by the clevis at its forward end its trunnions 20 follow the grooves 21 and pass over the humps 23 and drop down into the recesses 24. When in this position the trigger 19, resting on its trunnions 20, will support the coupling pin 14 out of engagement with the link 3. The cars may then be pulled apart at will.

When two cars are again brought together

the link 3, as it is held in alignment with its own head by its spring plunger 10, will enter the pocket 12 of the head B and is guided into the pocket by the sloping top and bottom walls 16 and 17 and the rearwardly converging side walls 26 of the pocket. The forward end of the link is bevelled to assist in guiding it into the pocket. As is shown in Fig. 2, as the link 3 enters the pocket its forward end strikes the free end 19^a of the trigger 19 and pushes it rearwardly, thus causing the trunnions to ride up out of the recesses 24 and over the humps 23 and drop down the inclines on the rear sides of the hump, and thus allow the trigger 19 to drop down into lowermost position and with it the coupling pin 14.

In buffering, the shape of the openings 3^a and 3^b in the link 3 for the pins 4 and 14 permits the link to move a sufficient distance into each head (the movement into the link head A being against the resistance of the spring plunger 10) to bring the forward faces of the heads A and B into buffering engagement.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. A link and pin coupler having a centrally disposed, horizontally pocket; a vertically movable coupling pin intended to engage a link in said pocket; and supporting means pivotally connected to the pin and arranged to hold the pin in uncoupled position; said means engaging one portion of the coupler head in coupled position and another portion in uncoupled position; said portions being separated by an intermediate raised portion, whereby accidental tripping of said supporting means is prevented.
2. A link and pin coupler having a centrally disposed, horizontal pocket; in com-

bination with a coupling link, attached to another coupler, adapted to be inserted into said pocket; a vertically movable coupling pin arranged to engage and be disengaged from said link; and a member for moving the pin into disengaged position and for supporting it therein, said member when the pin is in coupled position lying above the path of movement of said link and being adapted to be swung downwardly and forwardly into supporting position when the pin is in uncoupled position.

3. A link and pin coupler having a centrally disposed, horizontally extending pocket for reception of a coupling link; a pin supporting member; a vertically operated pin pivotally connected to the supporting member; the coupler having a plurality of longitudinally extending grooves in its head engaged by the supporting member; the supporting member being arranged to permit the pin to be moved automatically to non-supporting position.

4. A link and pin coupler having a centrally disposed horizontal pocket; a vertically movable coupling pin intended to engage a link in said pocket, a supporting member pivotally connected to the pin on a fixed axis forming a link in the pin operating mechanism and comprising means for supporting the pin in uncoupled position, the supporting member having a floating fulcrum engagement with the coupler head whereby the supporting member is movable from supporting to non-supporting position with respect to the pin.

5. A link and pin coupler having a centrally disposed, horizontally extending pocket for reception of a coupling link; a pin supporting member; a vertically operated pin pivotally connected to the supporting member; the coupler having a plurality of longitudinally extending grooves in its head engaged by the supporting member; the supporting member engaging one portion of the grooves to hold the pin in uncoupled position and another portion in coupled position.

DAVID ROBINSON.
